US0D1005262S

(12) **United States Design Patent** (10) Patent No.: **US D1,005,262 S**
(45) Date of Patent: ** Nov. 21, 2023

(54) **PORTABLE LOUDSPEAKER**

(71) Applicant: **Porsche Lizenz- und Handelsgesellschaft mbH & Co. KG**, Ludwigsburg (DE)

(72) Inventor: **Lisa Wolfsried**, Renningen (DE)

(73) Assignee: **Porsche Lizenz- und Handelsgesellschaft mbH & Co. KG**

(**) Term: **15 Years**

(21) Appl. No.: **29/824,793**

(22) Filed: **Jan. 27, 2022**

(30) **Foreign Application Priority Data**

Sep. 23, 2021 (EM) 008701056-0001

(51) **LOC (14) Cl.** **14-01**

(52) **U.S. Cl.**

USPC **D14/215**; D14/207

CLAIM

The ornamental design for a portable loudspeaker, as shown and described.

DESCRIPTION

FIG. 1 is a perspective view of a portable loudspeaker showing my new design;

FIG. 2 is a top view thereof;

FIG. 3 is a front view thereof, the rear view being a mirror image thereof;

FIG. 4 is a right view thereof; and,

FIG. 5 is a left view thereof.

The portions of the portable loudspeaker shown in broken lines form no part of the claimed design.

1 Claim, 5 Drawing Sheets
